United States Patent Office

Des. 212,537
Patented Oct. 29, 1968

212,537

AIRCRAFT WING MOUNTED SPEAKER

Charles R. Banks, 2350 Duke St.,
Alexandria, Va. 22314

Filed Jan. 19, 1968, Ser. No. 10,229

Term of patent 14 years

(Cl. D26—14)

FIG. 6

FIG. 1

FIG. 5

FIG. 1 is a perspective view of an aircraft wing mounted speaker, showing my new design;

FIG. 2 is an elevation as seen from the right of FIG. 1; FIG. 3 is a top plan view thereof;

FIG. 4 is a bottom plan view thereof;

FIG. 5 is an elevation as seen from the left of FIG. 1; and

FIG. 6 is a rear end elevation thereof.

The broken line fragmentary illustration of the aircraft wing in FIG. 1 is shown for illustrative purposes only.

I claim:

The ornamental design for an aircraft wing mounted speaker, as shown and described.
